CLAIM

We claim the ornamental design for a planting sensor, as shown and described.

DESCRIPTION

FIG. 1 is an isometric view of a planting sensor in accordance with an embodiment of the invention;

FIG. 2 is a front side view of a planting sensor in accordance with an embodiment of the invention;

FIG. 3 is a rear side view of a planting sensor in accordance with an embodiment of the invention;

FIG. 4 is a bottom side view of a planting sensor in accordance with an embodiment of the invention;

FIG. 5 is a top side view of a planting sensor in accordance with an embodiment of the invention;

FIG. 6 is a right side view of a planting sensor in accordance with an embodiment of the invention; and,

FIG. 7 is a left side view of a planting sensor in accordance with an embodiment of the invention.

The broken lines are for environmental purposes only and form no part of the claimed design. The design shown is not to be limited to any particular size and may be scaled larger or smaller.
